DESIGN FOR A NOVELTY PIN

George O. Fales, Los Angeles, Calif.

Application April 20, 1936, Serial No. 62,208

Term of patent 3½ years

To all whom it may concern:

Be it known that I, George O. Fales, a citizen of the United States, residing at Los Angeles, in the county of Los Angeles and State of California, have invented a new, original, and ornamental Design for Novelty Pins, of which the following is a specification, reference being had to the accompanying drawing, forming a part thereof, and in which:

I claim:

The ornamental design for a novelty pin as shown and described.

GEORGE O. FALES.
